PAPER ROLL HOLDER

Samuel N. Hope, Wauwatosa, Wis., assignor to
Griffith-Hope Company, West Allis, Wis., a corporation of Wisconsin

Application March 12, 1948, Serial No. 14,497

8 Claims. (Cl. 242—55.2)

1

The present invention relates to holders or dispensers for sheet material in roll form, such as paper toweling, toilet paper, and waxed paper.

An object of the invention is to provide an improved holder or dispenser for rotatably supporting a paper roll and frictionally retarding its rotation, and of such character as to facilitate the insertion of the roll and the removal of the roll core when the roll becomes exhausted.

Another object is to provide a roll holder which will protect and enclose the roll and which will permit easy severing or cutting of the paper.

A further object is to provide a roll holder which can be manufactured at relatively low cost and which presents a neat appearance.

The invention further consists in the several features hereinafter described and claimed.

In the accompanying drawings, illustrating certain embodiments of the invention,

Fig. 1 is a front elevational view of a loaded paper roll holder constructed in accordance with the invention;

Fig. 2 is an end view of the loaded holder;

Fig. 3 is a rear view of one end portion of the holder;

Fig. 4 is a transverse sectional view of the holder, taken generally on the line 4—4 of Fig. 1, an entering position of the roll being shown in broken lines;

Fig. 5 is a longitudinal sectional view of the holder taken generally on the line 5—5 of Fig. 2;

Fig. 6 is a sectional view similar to the right-hand portion of Fig. 5, but showing a slightly modified form of holder, a roll being shown in an entering position;

Fig. 7 is an end view of another modified form of holder, a roll being mounted therein, and

Fig. 8 is a sectional view of one end portion of the loaded holder of Fig. 7, taken generally along the line 8—8 of Fig. 7.

Referring to the drawing, the roll holder of Figs. 1 to 5 includes a supporting body or frame in the form of a horizontally extending housing or casing consisting of opposed sheet metal end members 10 and a sheet metal intermediate member 11 connecting the end members. The intermediate member 11 is bent to form a hood comprising a rear wall 12, a top wall 13, and an arcuate front wall 14 merging with the top wall, the bottom of the casing being open, and the front wall having a longitudinally extending lower edge 15 which is higher than the lower edge of the rear wall. Each end member 10 has a vertical end wall 16 and a curved inturned flange 17 along its rear, top and front, and the

2

ends of the member 11 have inwardly offset margins 18. The flanges 17 of the end members lap the offset margins 18 and are rigidly secured thereto, as by spot welding. The rear wall 12 has keyhole slots 19 adapted to receive screws 20 for attaching the holder to a supporting wall 21.

The vertical end walls 16 of the casing are parallel, and their inner faces form flat guide surfaces for the opposite ends of a roll 22 of sheet material, such as paper toweling, the roll having the usual tubular core 23. The distance between the parallel end walls 16 is slightly greater than the length of the roll, and the open bottom of the casing forms an entrance for the roll. The end walls 16 have respective circular, outwardly projecting embossments 24 aligned on a horizontal axis, each embossment having a flat vertical wall 25. Each end wall is further embossed to form an annular seat or rabbet 26 at the inner face thereof concentric with the main embossment 24. A flat, annular, sheet metal plate 27 has its peripheral portion fitting in the rabbet 26 and secured thereto as by spot welding 28, Fig. 4. The circular rabbet 26 facilitates the placement of the plate 27 and is of such depth that the plate is substantially flush with the inner face of the end wall 16, the plate presenting a roll-guiding surface. A chamber 29 is formed between each embossment 24 and the associated plate 27, and each plate has a central circular opening 30 through which projects a tiltably mounted bowl-shaped roll-engaging bearing member or follower 31 formed of sheet metal. The follower has a flat marginal stop flange 32 disposed in the chamber 29 and engageable with the adjacent face of the annular plate 27 to limit the projection of the follower. The convex portion of the follower, which is here shown to be spherically rounded, has a loose rotatable fit in the circular plate opening 30. The follower is urged in roll-engaging direction by a compressed coiled spring 33 confined in the chamber 29 between the flat embossment wall 25 and the concave side of the follower, the spring being restrained against lateral shifting by the concavity of the follower. In the absence of a roll, the spring urges the marginal stop flange 32 of the follower against the plate 27.

To insert a roll into the holder, the roll is grasped at its middle portion by one hand, lifted in a horizontal position between the guiding end wall surfaces of the holder, as seen in Figs. 4 and 6, and while held in an approximately horizontal position pushed directly upwardly until the convex portions or crowns of the followers seat in

the ends of the tubular roll core, as seen in Fig. 5. In this upward movement of the roll the roll ends exert a cam action on the convex portions of the followers, as seen in Fig. 6 (illustrating a slightly modified form of holder), causing tilting and depression of the followers. At this stage the upper end of each follower flange 32 fulcrums on the plate 27, and the upper edge of the convex portion of the follower abuts against the upper edge of the plate opening 30. When each follower is fully depressed the walls of the embossments 24 will prevent excessive lateral displacement of the follower. The tilting of the spring-pressed followers permits insertion of the roll with relatively small effort even though the follower springs are under adequate compression to hold the roll firmly in its dispensing position. The clearance between the periphery of the inserted roll and the adjacent walls of the holder is preferably small so as to facilitate centering of the roll. The loading operation is effected with one hand and requires very little time. As the roll reaches its centered position, each spring-pressed follower is free to tilt to a limited extent in any direction about the adjacent end of the coiled spring, thus distributing or equalizing the pressure contact of the convex portion of the follower with the adjacent end of the tubular roll core 23.

When a length of towel paper is desired, the protruding end of the paper is drawn downwardly a suitable distance and the paper is then severed along one of the usual lines of weakening, preferably by tearing the paper while in contact with the lower edge 15 of the casing front wall. The severing edge 15 is also used in the case of rolled paper without lines of weakening. The friction applied to the roll is sufficient to prevent free turning of the roll but will not interfere with normal dispensing. During rotation of the roll, the spring-pressed followers may or may not rotate, depending on the relative friction between the parts. If the free end of the paper should become inaccessible after a dispensing operation, it can be exposed by manually rotating the roll. After the roll is exhausted, the core can be easily removed by grasping it at its middle portion with one hand and pulling it downwardly to release it from the followers, the cam action of the core on the spring-pressed followers depressing the followers. Upon removal of the core, the followers are spring-urged to their stopped positions against the plates 27.

In the modification shown in Fig. 6, the lower edge of the casing end wall 16 has an outwardly curved portion or lips 34 to form a roll entrance. The construction is otherwise similar to that of Fig. 5.

The modified form of roll holder shown in Figs. 7 and 8 has a casing comprising an intermediate member 11 and opposed end members 10, one being shown. Each end member has a flat vertical end wall 35 with an inturned flange 17 secured to a marginal offset 18 formed on each end of the intermediate member 11, as in the device of Fig. 1. A cupped sheet metal member 36 is secured at the inner side of each end wall to form a chamber 37 therewith and has a flat vertical roll-guiding wall 38 and a cylindrical peripheral wall 39, the edges of the latter bearing on the inner face of the end wall 35. Bendable ears 40 formed on the edges of the cup wall 39 pass through slots 41 in the end wall 35 and are bent inwardly into correspondingly shaped depressions 42 formed in the end wall 35 to lie flush with the outer face of the latter wall. The cup

wall 38 has a central opening 30' through which extends a bowl-shaped roll-engaging follower 31' having a peripheral stop flange 32', the follower being urged in roll-engaging direction by a compressed coiled spring 33, as in the holder of Fig. 5. The holder of Figs. 7 and 8 is otherwise the same as the holder of Fig. 5, and is loaded and operated in the same manner.

Roll holders constructed in accordance with the invention can be used for dispensing various other sheet materials in roll form, such as toilet paper and wax paper.

What I claim as new and desire to secure by Letters Patent is:

1. In a holder for a roll of sheet material, a support having a roll-guiding wall with an opening, a spring-pressed follower having a convexly formed portion projecting loosely through said opening and adapted to interengage with the end of the roll for rotatably supporting the roll, and a spring for urging said follower against the end of the roll, said follower having a marginal stop flange behind and engageable with said wall to limit the projection of said follower, said convexly formed portion presenting a cam surface slidably engageable by the peripheral portion of the adjacent end of the roll for depressing said follower during the loading operation, and said follower being free to tilt in said opening to distribute the pressure contact of the follower with the end of the roll.

2. In a holder for a roll of sheet material, a support having a wall with an opening, a tiltably mounted follower having a convexly formed portion projecting loosely through said opening and adapted to interengage with the end of the roll, said follower having a marginal stop portion engageable behind said wall to limit the projection of the follower and to form a fulcrum during tilting of the follower, and spring means for urging said follower in roll-engaging direction and for yieldably resisting the tilting displacement of said follower, said convexly formed portion presenting a cam surface slidably engageable by the peripheral portion of the adjacent end of the roll for tilting and depressing said follower during the loading operation.

3. In a holder for a roll of sheet material, a support having end walls each with an embossment, a pair of parallel roll-guiding plates secured to the inner sides of said respective end walls to form chambers with said embossments, said plates having respective openings therein and adapted to guide the opposite ends of the entering roll, tilttable followers having convex portions projecting loosely through said respective openings and adapted to interengage with the opposite ends of the roll for rotatably supporting the roll, each follower further having an annular marginal stop flange engageable behind the adjacent end wall to limit the projection of said follower and to fulcrum on said end wall, the convex portion of said follower being laterally engageable with the edge of the associated opening to limit the lateral displacement of said follower, and spring means in said chambers for urging said followers in roll-engaging direction, said convex follower portions presenting cam surfaces slidably engageable by the peripheral portions of opposite ends of the roll to push said followers apart during the loading operation.

4. In a holder for a roll of sheet material, a support having spaced walls, a pair of cup-shaped members secured to the inner faces of said respective walls to form chambers therewith and

5. In a holder for a roll of sheet material, a support having a wall with an opening, a tilttable follower having a convexly formed portion projecting loosely through said opening and adapted to interengage with the end of the roll, said follower having a marginal stop portion engageable behind said wall to limit the projection of the follower and to form a fulcrum during tilting of the follower, and spring means for urging said follower in roll-engaging direction and for yieldably resisting the tilting displacement of said follower, said convexly formed portion presenting a cam surface slidably engageable by the peripheral portion of the adjacent end of the roll for tilting and depressing said follower during the loading operation.

6. In a holder for a roll of sheet material, a support having end walls each with an embossment, a pair of parallel roll-guiding plates secured to the inner sides of said respective end walls to form chambers with said embossments, said plates having respective openings therein and adapted to guide the opposite ends of the entering roll, tilttable followers having convex portions projecting loosely through said respective openings and adapted to interengage with the opposite ends of the roll for rotatably supporting the roll, each follower further having an annular marginal stop flange engageable behind the adjacent end wall to limit the projection of said follower and to fulcrum on said end wall, the convex portion of said follower being laterally engageable with the edge of the associated opening to limit the lateral displacement of said follower, and spring means in said chambers for urging said followers in roll-engaging direction, said convex follower portions presenting cam surfaces slidably engageable by the peripheral portions of opposite ends of the roll to push said followers apart during the loading operation.

7. In a holder for a roll of sheet material, a support having spaced walls, a pair of cup-shaped members secured to the inner faces of said respective walls to form chambers therewith and

8. In a holder for a roll of sheet material, a support having a wall with an opening, a tilttable follower having a convexly formed portion projecting loosely through said opening and adapted to interengage with the end of the roll, said follower having a marginal stop portion engageable behind said wall to limit the projection of the follower and to form a fulcrum during tilting of the follower, and spring means for urging said follower in roll-engaging direction and for yieldably resisting the tilting displacement of said follower, said convexly formed portion presenting a cam surface slidably engageable by the peripheral portion of the adjacent end of the roll for tilting and depressing said follower during the loading operation.

9. In a holder for a roll of sheet material, a support having a wall with an opening, a tilttable follower having a convexly formed portion projecting loosely through said opening and adapted to interengage with the end of the roll, said follower having a marginal stop portion engageable behind said wall to limit the projection of the follower and to form a fulcrum during tilting of the follower, and spring means for urging said follower in roll-engaging direction and for yieldably resisting the tilting displacement of said follower, said convexly formed portion presenting a cam surface slidably engageable by the peripheral portion of the adjacent end of the roll for tilting and depressing said follower during the loading operation.

having plate-like wall portions with respective openings, said wall portions being adapted to receive the roll between them and to guide the opposite ends of the entering roll, followers projecting loosely through said respective openings and adapted to interengage with the opposite ends of the roll for rotatably supporting the roll, said follower having a marginal stop flange behind said wall portion to limit the projection of the follower, and springs in said chambers interposed and confined between said walls and said followers for urging said followers in roll-engaging direction, said followers having cam-forming surfaces slidably engageable by the peripheral portions of the opposite ends of the roll to push said followers apart during the loading operation.

5. In a holder for a roll of sheet material, a support having a wall with an opening, a bowl-shaped roll-supporting follower rotatably projecting through said opening and having a marginal stop flange behind said wall and adapted to fulcrum on said wall, and spring means for urging said follower in roll-engaging direction, said follower adapted to interengage with an end of the roll for rotatably supporting and braking the roll end and having a cam surface slidably engageable by the peripheral portion of the roll end for depressing said follower.

6. In a holder for a roll of sheet material, a support having end structures adapted to admit the roll between them, said end structures each having inner and outer wall portions, said inner wall portions having respective openings and presenting guide surfaces for the opposite ends of the entering roll, followers projecting through said respective openings and adapted to interengage with the opposite ends of the roll for rotatably supporting the roll, each follower having a marginal stop flange behind the inner wall portion to limit the projection of the follower, and springs interposed and confined between the outer wall portions and said followers for urging the followers in roll-engaging direction, said followers having cam surfaces slidably engageable by the peripheral portions of the opposite ends of the entering roll to push said followers apart

during the loading operation, and each follower having a limited freedom to tilt in any direction.

7. In a holder for a roll of sheet material, a support having an end wall with an embossment and an inner annular rabbet around the base of said embossment, a flat plate marginally secured to said embossed wall to form a chamber therewith and fitting in said rabbet to lie substantially flush with the inner face of said wall, said plate having a central opening, a follower having a convexly rounded portion extending loosely through said opening and further having a stop portion within said chamber and a concave side facing said wall embossment, and a spring in said chamber for urging said follower in roll-engaging direction, said spring being confined between said end wall embossment and the concave side of said follower.

8. In a holder for a roll of sheet material, a support having a wall with an opening and presenting a guiding surface for the end of the roll, a tiltably mounted follower having a convexly formed portion projecting loosely through said opening and adapted to interengage with the end 25 of the roll for rotatably supporting the roll end, said follower having a marginal stop portion behind said wall for limiting the projection and tilting displacement of said follower, and spring means behind said follower for urging said follower in roll-engaging direction and for yieldably resisting tilting of said follower, said convexly formed portion presenting a cam surface slidably engageable by the peripheral portion of the roll end for tilting and depressing said follower during the loading operation.
